[57] CLAIM

The ornamental design for suspenders, as shown and described.

DESCRIPTION

FIG. 1 is a top and left side perspective view of suspenders showing my new design;

FIG. 2 is a left side elevational view of an enlarged scale, the strap having been omitted for ease of illustration;

FIG. 3 is a bottom plan view on an enlarged scale, the strap having been omitted for ease of illustration;

FIG. 4 is a rear elevational view on an enlarged scale, the strap having been omitted for ease of illustration;

FIG. 5 is a front elevational view on an enlarged scale, the strap having been omitted for ease of illustration;

FIG. 6 is a left side elevational view on an enlarged scale, the strap having been omitted for ease of illustration; and

FIG. 7 is a top plan view on an enlarged scale, the strip having been omitted for ease of illustration; and

FIG. 8 is a rear perspective view thereof.

FIG. 1

FIG. 7.**FIG. 2.****FIG. 3.****FIG. 4.****FIG. 5.****FIG. 6.***FIG. 8*
